APPARATUS FOR PERMANENTLY WAVING
HAIR

Julius Wenter, Budapest, Hungary

Application May 27, 1935, Serial No. 23,564
In Hungary October 17, 1934

6 Claims. (Cl. 132—33)

This invention relates to hair-waving devices, the principal object of the invention being to provide a device of this character having means for maintaining the coils of the hair in separated relation, in combination with means for exerting tension on said coils during treatment.

A further object of the invention is to provide a device of the character set forth, having means for supporting the curler and the necessary heating element, said means being effective to prevent burning of the scalp of the person being operated on.

A still further object of the invention is to provide a curling device in combination with a heating element having special means for removably securing the heating element and curler together.

In the drawing accompanying this specification,

Fig. 1 shows a hair waving device partly in vertical longitudinal section and partly in side elevation embodying the features of the present invention, with a tress of hair wound in the curler;

Fig. 2 shows the clip-like supporting plate of the curler in plan, the full lines indicating the closed position and the dot-dash lines the open position thereof;

Fig. 3 is a longitudinal section of the curler;

Figs. 4 and 5 illustrate opposite end views of

Fig. 3;

Fig. 6 is a longitudinal sectional view of the curler showing the hair-tensioning device in the outer or tensioning position;

Figs. 7 and 8 are transverse sectional views on an enlarged scale, taken respectively on lines VII—VII of Fig. 3 and VIII—VIII of Fig. 6.

The curler according to the invention consists of a preferably cylindrical spindle 1, the surface of which is provided in known manner with 40 teeth, pegs or pins 2, or the like, as shown in Figs. 1, 3, and 6. The said teeth may be arranged in the manner of a comb along one line or generatrix, as shown in the drawing.

This construction of the curler enables the 45 tress of hair which is to be waved to be wound around the same in any desired manner, for example, in spirals of any desired pitch or in the form of a figure 8 and so on, without the 50 danger of the coils mingling together or changing their position in any other way relatively to the curler and to one another. This is effected by means of the described teeth or pins between and in which the tress of hair is wound 55 on to the curler, and which secure the coils in

the form and position which they have been given.

In order to impart a smooth form to the waves which are to be produced, the tress of hair which has been wound on the curler must be tightened 5 or tensioned accordingly before the curler is inserted into the heating device. For this purpose according to the invention, the curler is provided with a semi-tubular member 9 which embraces the curler 1 on the untoothed side 10 thereof and which is radially displaceable relatively to the curler 1 by means of a wedge member 11 disposed in an open longitudinal groove 10 formed in the curler 1, said groove having tapered end walls as indicated at 1', Figs. 3 and 6, 15 against which the ends of the wedge member 11, abut, while its peripheral edge is in contact with the inner surface of member 9. The wedge 11 is in position to be acted upon in a longitudinal direction by a screw 12 threaded into the end of 20 curler 1. In Fig. 3 this wedge-displacing device is shown before the displacement of the wedge, while Fig. 6 shows it after such displacement. The simultaneous axial and radial movement of the wedge 11 is brought about by the 25 fact that its tapered front end in contact with the similarly-inclined end wall of the groove 10 in the curler member 1 rides up on said end wall, and when it is displaced axially it is compelled 30 at the same time to rise in a radial direction. 30 The screw 12, which when screwed into the curler member 1, strikes with its inner end against the wedge 11, is provided at its outer end with a square portion 13 to enable it to be rotated readily by means of a key. It is clear 35 from Fig. 6 that in its displaced position the member 9 must tension the coils of hair lying on the curler. Obviously the displaceable member 9 may also be provided with the described 40 hair-locating pins or pegs 2.

In order to facilitate the winding of the tress of hair which is to be waved and to hold it near to the head during the winding operation, and also to protect the scalp from being burned, a clip 45 such as shown in Fig. 2 is provided. This clip consists of two plates 4 and 4' of heat-resistant elastic material, for instance, advantageously of soft rubber, which are connected together by means of a hinge 6. After the hair which is to be wound has been placed between the two plates 4 50 and 4', the latter are adapted to be closed fast together by means of any suitable closure device, which in the construction illustrated consists of a clasp fastener 7 as shown in full lines in order 55 to clasp the tress of hair 8 between them near the

roots, as shown in Fig. 1. The plate 4 of this clip has an obliquely and upwardly extending projection 5 preferably of rectangular cross-section, adapted to fit snugly into an opening 3 of similar cross section formed in one end of the curler 1 so that when placed on said projection 5, the curler is prevented from rotation relatively thereto. The ends of the semi-tubular member 9 of the curler are closed by plates 14 and 15 respectively having slot-like openings 14' and 15' respectively to allow the passage of the screw 12 at one end and the projection 5 of the clip at the other end. These slots not only guide the member 9 of the curler in its movement in radial direction and prevent it from becoming detached from the member 1, but at the same time serve as spacers to hold the curler at a uniform distance from the wall of the heating element of the waving apparatus.

20 After the hair, which is held firmly by means of the clip 4, 4' has been wound on to the curler which likewise is supported firmly by the clip by means of the projection 5 on the latter, the heating element 16 which is known per se and is preferably of channel-shaped cross section, is placed on the curler. The heating element is provided with a two-armed clamping lever 18, which is hingedly connected to the heater by means of a pivot 17, one of the arms of said lever being urged against the channel-shaped opening of the heating element 16 by means of a spring, the said arm carrying at its free end a foot member 19 by means of which it presses against the under side of the curler and holds the heating element 16 firmly to the curler.

35 What I claim is:

1. A hair-waving device, comprising in combination, an integral cylindrical curler toothed along a generatrix thereof for the reception of coils of hair, means carried by said curler for tensioning the hair wound thereon, a channel-shaped heating element embracing the curler on three sides, leaving the lower side exposed and supporting means for attaching the curler to the tress of hair near the roots thereof, said supporting means, consisting of a two-parted hinged clamp, provided on one of its branches with an oblique, upwardly pointed spur of prismatic end section, fitted removably into a prismatic and axially positioned socket in the curler, thereby preventing spontaneous rotation of the curler, relative to its support.

2. A hair-waving device, comprising in combination, a cylindrical curler, adapted to receive coils of hair, a semi-tubular member embracing said curler, a member carried by said curler in peripheral contact with the inner surface of said semi-tubular member and movable longitudinally and radially of the curler, means carried by the curler for imparting longitudinal movement to said movable member, and cooperating means carried by the curler and movable member whereby the latter will move radially in response to such longitudinal movement thereby to move said tubular member radially of the curler and impart tension to the hair wound thereon.

3. A hair-waving device, comprising in combination, a cylindrical curler adapted to receive coils of hair, a heating element embracing the curler, a pivoted lever carried by said heating element, said lever having a spring-actuated arm for engaging said curler and retaining it in operative engagement with the heating element.

4. A hair-waving device according to claim 1, in which the two-parted hinged clamp consists of two rectangular thick plates 4 and 4', lying adjacently in the same plane and linked together at two adjacent corners by a hinge 6, perpendicular to said plane, so that they may be opened and closed within the same plane, the closure means consisting of a bow-clasp 7, while the spur, supporting the curler, is fixedly attached to the top surface of one of said plates.

5. A hair-waving device according to claim 1, in which the hair-tensioning means consists of a semicylindrical plate sleeve 9 which may be spaced apart from and parallel to the axis of the curler by an inner wedge, supporting said sleeve, said wedge guided in an open longitudinal slot 10 of the curler 1 and adapted to be radially lifted out of the slot in parallel motion by a screw 12, axially journalled in the cylindrical curler.

6. A hair-waving device according to claim 1, characterized by the feature that the channel-shaped heating element 16, which otherwise is of well-known construction, is provided with a two-armed clamping lever 18, pivotally supported by 45 said element and rotatable within the median plane thereof, one of the lever arms having a claw 19, actuated by a spring, so that by pressing inwardly toward the open channel said claw is adapted to clamp the curler against the heating element.

JULIUS WENTER.
